UNITED STATES PATENT OFFICE.

FRANKLIN H. JOHNSON, OF AURORA, ILLINOIS, ASSIGNOR TO LYON METALLIC MANUFACTURING COMPANY, OF AURORA, ILLINOIS, A CORPORATION OF ILLINOIS.

FILING-ENVELOP.

1,206,442.

Specification of Letters Patent. Patented Nov. 28, 1916.

Application filed March 23, 1916. Serial No. 86,181.

To all whom it may concern:

Be it known that I, FRANKLIN H. JOHNSON, a citizen of the United States, residing at Aurora, in the county of Kane and State 5 of Illinois, have invented a certain new and useful Improvement in Filing-Envelops, of which the following is a specification.

My invention relates to envelops, more especially for filing purposes. In order to 10 explain the nature of my invention, I will describe one advantageous use to which it may be put. It is customary for merchants to send out catalogues which the merchant intends shall be kept by the recipient who 15 is a prospective customer. These catalogues are frequently expensive and contain data and information calculated to benefit both the seller and the purchaser, but the prospective customer may not have immediate 20 need for the goods advertised and although he would gladly preserve the catalogue, he is apt to destroy it or throw it away simply for the lack of convenient means for storing it and for having it immediately accessible 25 in a well known place when the time comes for him to use it. Card files or index files of standard sizes are possessed by innumerable enterprising business concerns, but these files have not been adapted for the 30 accommodation of catalogues, nor ready reference thereto.

The object of my invention in its broadest aspect is to provide means for rendering such catalogues, booklets and brochures accessible for immediate reference with as 35 much ease and certainty as any other article in a standard index file. In a narrower aspect, it is my purpose to provide a container for a catalogue or booklet which, 40 when arriving at its destination, may be opened without injury, and when in open condition is fit to take its place in a standard file as one of the indexed articles of said file, said container still maintaining its 45 ability to contain the article which is enclosed during transmission from the seller to the prospective buyer.

I accomplish my object by the construction illustrated in the accompanying drawings, in which—

Figure 1 is a perspective view of the back of an envelop embodying my invention. In this figure the envelop is shown in open position as it will appear in use in the file. 55 Fig. 2 is a perspective view of the back

of an envelop embodying my invention, the same being shown in closed position as it will be transmitted through the mails or by messenger. Fig. 3 is a perspective of a file utilizing my invention.

Similar numerals refer to similar parts throughout the several views.

The envelop has a body 1, provided with a flap 2. The outer or free edge 3 of this flap is substantially parallel with the bottom edge 4 of the envelop. The envelop when closed is rectangular in outline. An indexing strip 5 is formed at the outer edge of the flap and has a suitably designated space 6 for the reception of the name and address of the sender of the catalogue, or whatever is contained within the envelop. The outer edge of the strip 5 is parallel to the bottom of the envelop and the shape and size of the envelop, flap and strip is such, 70 and the location of the strip is such that when the envelop is in open condition, as shown in Fig. 1, the outline will conform to the cards of some standard size of index. To illustrate: A 7x10" catalogue may appropriately be mailed in an envelop approximately 12 in. long and approximately 9 in. high from the bottom edge of the envelop to the upper edge of the flap when open. For such an envelop the flap may 80 appropriately be 1 $\frac{1}{2}$ in. deep, but it will be understood that these sizes are a matter of choice, it being the policy of the sender to employ an envelop, which, when open, 85 will conform to some commonly accepted or 90 standard size of file.

In the preferred construction, the parts of the envelop above described are all integral with each other, the material itself being comparatively stiff and the flap being 95 scored or otherwise rendered partially flexible at the juncture of the flap to the body of the envelop.

A suitable fastening device is employed for holding contents within the envelop 100 during transmission and this fastening device is of a kind which will permit the envelop to be opened without damage to it. An advantageous form of fastener is shown in Figs. 1 and 2; this consisting of two 105 disks 7 and 8 fastened to the back of the body of the envelop and to the outside surface of the flap and adapted to frictionally engage a string 9 in the well known manner.

After the catalogue or booklet has been 110

inserted at the office of the sender, the envelop is closed as in Fig. 2 and then transmitted to the prospective customer. The customer, upon receipt, opens the envelop by unfastening the string and is then free to examine the contents. If the catalogue or booklet is one which the customer wishes to keep, he reinserts the contents, or so much thereof as he may wish to keep, opens up the flap as shown in Fig. 2 and inserts the whole in the file box or drawer 10 in the manner indicated in Fig. 3. Under these conditions the name of the sender appears on the index strip 6 in the same relative position in the box that the other index strips occupy and thereupon the catalogue becomes available at any time for reference and occupies but a small compass. These advantages influence the recipient to preserve the catalogue, to his own and to the sender's advantage, and many catalogues are thus kept which would otherwise be destroyed. The recipient does not have even the trouble of placing the indicia upon the index strip for this, under normal conditions, will be done for him by the sender. As this matter will ordinarily be printed, it can be done at very little expense per envelop and, being printed, will be very legible and even attractive in appearance.

Having thus described my invention, what I claim as new and desire to secure by Letters Patent, is:—

1. An envelop having a flap at the top adapted to fold against the body of the envelop to thereby form a closure for the envelop, said flap having a suitably designated space on the inner surface for indicia, whereby, when the flap is closed the indicia are covered and when the flap is in upstanding position the indicia appear above the body of the envelop and on the same side as the opening of the envelop.
2. An envelop having a flap at the top adapted to fold down against the body of the envelop to close it, and an index strip on the flap arranged to stand upright when the flap is open and upright, the indicia bearing surface of the strip being on the inside to consequently be covered when the flap is closed and to be exhibited above the

opening of the envelop when the flap is upstanding, the top edge of the index strip being parallel to the line of fold of the flap.

3. A mailing envelop closed at the bottom and ends and having a flap at the top adapted to fold over the opening of the envelop, an index strip on said flap, said strip standing upright when the flap is open and upright, the upper edge of the strip being parallel to the line of fold of the flap, and a fastening device for said flap, a part of said fastening device engaging the index strip and passing over the outside thereof.

4. An envelop having a flap provided with an indexing strip rising from its outer edge, the outer edges of the strip and of the remainder of the flap being parallel to the bottom of the envelop, the index strip having an unobstructed space for the indicia on the inner surface of the strip whereby the indicia are protected and covered when the envelop is closed.

5. An envelop having a flap provided with an indexing strip rising from its outer edge, the outer edges of the strip and of the remainder of the flap being parallel to the bottom of the envelop, the index strip having a suitably designated space for the indicia on the inner surface of the strip whereby the indicia are protected and covered when the envelop is closed, and means for fastening and unfastening the envelop without damage thereto.

6. An envelop having a flap provided with an indexing strip rising from its outer edge, the outer edges of the strip and of the remainder of the flap being parallel to the bottom of the envelop, the index strip having a suitably designated space for the indicia on the inner surface of the strip whereby the indicia are protected and covered when the envelop is closed, and means for fastening and unfastening the envelop without damage thereto, said fastening means coming on the outside of the flap to thereby avoid interfering with the viewing of the indicia when the envelop is open.

In witness whereof, I have hereunto subscribed my name.

FRANKLIN H. JOHNSON.
